UNITED STATES PATENT OFFICE.

SYLVANUS D. LOCKE, OF HOOSICK FALLS, NEW YORK.

HARVESTER-BINDER.

SPECIFICATION forming part of Letters Patent No. 249,472, dated November 15, 1881.

Application filed April 11, 1879.

To all whom it may concern:

Be it known that I, SYLVANUS D. LOCKE, of Hoosick Falls, in the county of Rensselaer and State of New York, have invented a certain new and useful Improvement in Harvester-Binders; and I do hereby declare the following to be a full, clear, and exact description of the same, reference being had to the accompanying drawings, forming part of this specification, in which—

Figure 1 is a top-plan view of a harvester-binder, showing the application of my improvements. Figs. 2 and 3 are elevations of the binding apparatus, and Fig. 4 is a detached view of a cord-holder.

Similar letters of reference in the several figures denote the same parts.

This invention relates more particularly to that class of automatic grain-binders in which the binding-table and binding mechanism are capable of being adjusted with relation to the length or position of the grain; and my improvements consist in combining with the adjustable frame which supports the band-carrying arm a sliding block mounted upon a harvester above the elevator and connected with and partaking of the movements of said frame, and a seat for the band-spool upon said sliding block; in an improved arrangement of binding or band-carrying arm, band spool or holder, and driver's seat, whereby the driver is enabled to thread the binding-arm with facility without rising from his seat, and in certain features of construction, hereinafter described and claimed.

In the drawings, A represents the harvesting-machine; B, the binding-table, and G the adjustable frame which supports the band-carrying arm I and the compressor and separator J. The frame G is mounted upon two traveler-rods, f f, supported in a casting or castings, F, affixed to the lower part of the harvester-frame, and is adjusted in position by sliding it back and forth on the rods by means of a suitable lever, H, extending within reach of the driver on the seat a', or by any practically equivalent device.

Inasmuch as the construction of the frame G and of the binding mechanism connected therewith is set forth and claimed in other pending applications filed by me for Letters Pat-

ent thereon, and as any approved forms thereof may be used, I do not deem it necessary to more fully describe the same in this application; but I will pass at once to those parts of the machine which form the subject-matter of the invention claimed herein.

Upon the upper cross-bar, C, of the harvester-frame, above the discharge end of the grain conveyer or elevator, I arrange a suitable guide-rail, E, having a projecting guide-rib, e, or the practical equivalent thereof, and upon this rail I mount a sliding or traveling block or carriage, K, having, if preferred, friction-rollers k to run in contact with the rail on one or both sides and prevent cramping, and preferably having either the edge of the rollers or some part of the block or its attachments projecting under the rail E, or a flange thereon, to hold the block or carriage down to its work. From the opposite ends of this block two stout stay rods or bars, L L', extend to and are attached in any manner to the opposite ends of the adjustable frame G at its top. I prefer to secure them thereto by screw-nuts l l, whereby the frame can be inclined more or less to the cross-bar C, as may be desired. The block or carriage K should be of considerable length, so that the ends of the rods or braces L L', where they are connected to it, may be widely apart, in order that they shall hold the frame G stiffly and prevent it from twisting or vibrating under the strain to which it is subjected. The top of the frame G and the carriage K will be parallel to each other, and the two braces L L', attached to the opposite ends of the frame G, will extend nearly or quite parallel to each other; or crossed diagonals may be used, if preferred, the essential thing being to get the ends of the braces widely apart, so that they will brace and hold the frame more rigidly.

The braces are secured to both the frame and the sliding block K by some species of rigid connection which will hold the parts stiff, and prevent any bending or yielding at the points. They are represented in the drawings as secured to the part K by being inserted into cylindrical sockets, and to the part G by passing through it, and having stout screw-nuts on either side to clamp them firmly to the frame; but I do not limit myself to these two modes of connection. As the frame G is moved along

the rails *f*, it is evident that the braces *L L'* will cause the block *K* to slide on its supporting-rail, and thus always maintain the proper relative position to the frame, and that, however the frame *G* may be adjusted, the said braces will hold it steadily against lateral vibration, and thus keep the parts of the binding mechanism in accurate working relation with each other.

10 I come now to the wire-reel, tension, and take-up devices, which are constructed as follows:

15 *M* is a standard, preferably stepped in a socket in the block *K*, and hence sliding therewith, so as to preserve the proper position with relation to the band-carrying arm *I*. At its upper end the post *M* is provided with a stout horizontal arm or bracket, *m*, Fig. 1, which supports a rigid bar or rod, *m'*, which in turn supports another stout arm, *m''*, parallel to the arm *m*. The spool or wire-reel *N* is mounted upon a suitable shaft in bearings formed in the arms *m m''*, as shown. A curtain, *O*, hung upon the rod *m'*, rests upon the spool and hangs down behind it, and at its lower end it is weighted 25 as shown at *o*. This device serves as a tension or brake to the spool, and at the same time covers it from dust and dampness.

30 *P* is a spring take-up arm, mounted on a projecting end of the rod *m'* by means of a sleeve-bearing fitted thereon, and having a coiled spring, *s*, to keep it under the proper tension, and a stop, *s'*, to limit its backward movement. The wire passes from the spool under the rod *m'*, thence over a sliding and rotating grooved 35 pulley, *p*, mounted on the spring arm *P*, and thence to the point of the band-carrying arm *I*. The sliding pulley adjusts itself automatically to the feed of the wire from the spool *N* and the position of the arm *I*. The rod *P* yields 40 as the wire is drawn off by the arm *I*, but springs back and takes up the slack of the band as the arm *I* moves around to take position for binding a new gavel. The spool *N* is, by this arrangement upon the top rail or cross-bar of the 45 harvester, brought so near to the driver that it is no longer necessary, as heretofore, for him to stop the team, get down out of his seat, and go around the end of the frame, in order to adjust the spool or apply a new one; but he can,

while sitting in his seat, remove the spool, place 50 a new one on the shaft, and, reaching over the cross-bar *C*, he can easily thread the wire through the arm *I*, thereby saving much time and trouble. In case wire is not used for the bands, the cord-holder, of whatever form it may 55 be, is to be located upon the cross-bar *C* by being secured to the traveling block *K* by means of a standard, *M*, or its equivalent. This construction is shown in Fig. 4, where *Q* represents the cord-holding box, and *P* the tension take-up, mounted on a standard, *M*.

I do not herein claim the band-securing devices, nor the separator and compressor, nor the binding-table, nor the reel, as I have prepared and am about to file applications for separate Letters Patent upon said improvements; but

I claim as my invention—

1. In combination with the adjustable frame which supports the band-carrying arm of a 70 grain-binder, a sliding block mounted upon the harvester above the elevator, and connected with and partaking of the movements of said frame, and a seat for the band-spool upon said sliding block.

75 2. In a harvester and binder, the combination of a band-carrying arm adjustable back and forth upon the harvester-frame, and a wire-spool or cord-holder similarly adjustable, the the two being arranged in such manner that 80 as the point of the arm approaches the spool or holder its eye and said spool or holder shall both be within reach of the driver while sitting in his seat, substantially as described.

3. The combination of the guided block *K* 85 and braces *L L'* with the harvester-frame, the band-carrying arm, and the wire-spool or cord-holder, whereby said arm and said spool or holder may be shifted in their position on the harvester-frame, to adjust them to the length 90 of the grain, and yet maintain them within reach from the driver's seat, substantially as described.

SYLVANUS D. LOCKE.
